UNITED STATES PATENT OFFICE.

PERCY M. CROCKETT, OF NORRISTOWN, LOUIS J. EHLINGER, OF CONSHOHOCKEN, AND JAMES J. POWERS, OF WEST CONSHOHOCKEN, PENNSYLVANIA.

AUTOMATIC CONDENSATION-PUMP.

1,373,304.

Specification of Letters Patent. Patented Mar. 29, 1921.

Application filed December 6, 1919. Serial No. 342,945.

To all whom it may concern:

Be it known that we, PERCY M. CROCKETT, LOUIS J. EHLINGER, and JAMES J. POWERS, citizens of the United States, residing, respectively, at Norristown, Conshohocken, and West Conshohocken, in the county of Montgomery and State of Pennsylvania, have invented a new and useful Automatic Condensation-Pump, of which the following is a specification.

This invention is an apparatus for automatically disposing of the condensation resulting from the use of steam as a source of power.

One of the objects of the invention is to provide a trap or receptacle into which the water of condensation may accumulate, and means coöperating with the receptacle to automatically empty it when the accumulated liquid reaches a predetermined volume. A further object is to provide means whereby steam pressure may be employed to empty the receptacle of the accumulated liquid. A further object is to provide means whereby the weight of the water of condensation is utilized to control the admission of steam to the receptacle for the purpose of emptying the latter.

The invention will be hereinafter fully set forth and particularly pointed out in the claims.

In the accompanying drawings:—

Figure 1 is an end view illustrating an automatic condensation pump constructed in accordance with the invention. Fig. 2 is a plan view thereof. Fig. 3 is a side view with parts in section, showing the tank in tilted position. Fig. 4 is an enlarged sectional view on the line 4—4 Fig. 2. Fig. 5 is an enlarged transverse sectional view on the line 5—5 Fig. 2. Fig. 6 is a detail perspective view illustrating the trunnioned shaft and cam.

Referring to the drawings, 10 designates a base to which are secured in suitable manner, bearings 11 and 12, which support an oscillatory trunnion shaft 13. The ends of the shaft extend through stuffing boxes which may be of any desired construction, but illustrated as consisting of spaced apart packing rings 14 and an interposed adjustment spring 15, retained in place by a suitable gland 16.

The shaft 13 is provided with an enlargement 17 between its ends, to which is re-

movably secured by means of bolts 17^a, a pad 18 attached to the underside of a tank or receptacle 19. Said tank is divided into a reservoir 20, and a counter-weight chamber 21, the latter containing sand or any other weighting material conveniently illustrated at 22. The base 10 is provided with stops 23 and 24 for limiting the rocking movement of the receptacle 19 because of its attachment to the trunnion shaft 13. 65

The bearing 11, is provided with an opening 25 to receive the end of a supply pipe 26. The shaft 13 is provided with a conduit 27 registering with the opening 25 and forming a continuation of the pipe 26, said conduit having a chamber 28 within the enlarged portion 17 of the shaft. The reservoir 20 communicates with the chamber 28 through the medium of a nipple 29, connected by a suitable elbow 29^a to a discharge pipe 30, which extends along the reservoir, near the bottom thereof, its discharge end being located at the far end of the receptacle. The nipple 28 is provided with a headed end which coöperates with the elbow 29^a, to clamp the pad 18 and the tank 19, to thereby provide a rigid support for the pipe 30. For the purpose of facilitating the insertion and removal of the pipe 30 and for inspecting and cleaning, the receptacle is provided with an opening 31 contiguous to the end of pipe 30 said opening being normally closed by a removable plug 32. 85

The bearing 12 is provided with an extension in which is formed a chamber 35, which communicates with the reservoir 20 through a conduit 36 formed in the shaft 13, and a discharge pipe 37 extending vertically into said reservoir. The pipe 37 is 90 removably supported by means of a nipple 37^a to which it is connected, said nipple being threaded to engage a threaded opening in the pad 18. The shaft 13 is provided with a cam 38 located within the chamber 35, and provided with two abutments 39 and 40, positioned to engage the stems of a steam valve 41 and of a vent valve 42, said valves being normally held to their seats by suitable springs 43. The valve 41 is located in a valve chamber 44 connected with a steam supply pipe 45. The valve 42 is located within a valve chamber 46 communicating with a pipe 47, open to the atmosphere. 105 110

The condensation pipe 26 is connected in suitable manner, for instance by a T-coupling 48, with a supply pipe 49 and a discharge pipe 50. The pipe 49 is provided 5 with a check valve 51 and the pipe 50 is provided with a check valve 52.

In operation the receptacle 19 when empty, occupies the position illustrated in dotted lines in Fig. 3. The water of condensation flows through the pipe 49 into the branch 26, through the conduit 27 and nipple 29 and the attached pipe 30 into the reservoir 20. When the receptacle is in the position illustrated in dotted lines 15 Fig. 3, the cam 38 is in the position illustrated in full lines Fig. 4, the vent valve 42 being raised and the steam valve 41 seated. Thus as water flows into the reservoir 20 the said reservoir is vented through 20 pipe 37, conduit 36, chamber 35 and vent pipe 47. When a sufficient quantity of water has accumulated in the reservoir 20 to over-weight the counter-balance 22, the receptacle tilts to the position illustrated 25 in full lines in Fig. 3. The effect of this tilting action is to cause the cam 38 to shift its position, so that the vent valve 42 is seated and the steam valve 41 is unseated, whereupon steam under pressure is admitted from pipe 45 to the chamber 35, and passes through the conduit 36 and pipe 37 into the reservoir, above the level of the water in the latter. The pressure of the steam upon the surface of the water causes 35 the latter to flow back through the pipe 30 and the conduit 27, to the discharge pipe 50, the pressure closing the check valve 51 and raising the check valve 52. The pipe 50 may, of course, lead to any desired locality. When the reservoir 20 is emptied, 40 the counter-weight material will cause the receptacle 19 to return to the dotted line position of Fig. 3, whereupon the cam 38 will unseat the vent valve 42 and permit 45 the spring 43 to seat the steam valve 41. The parts remain in this position until the receptacle is again tilted because of an accumulation of water in the reservoir 20. It will be noted that the valve springs 50 43 in addition to performing their functions in seating the valves also serve to cushion the receptacle in its rocking movement, through the cam or tappet 38.

In assembling the parts, the elbow 29^a 55 is connected with the pipe 30, and together with the pipe, is inserted through opening 31, being moved to a position where it may be engaged by the nipple 29. As the latter is screwed home, the elbow is brought firmly 60 against shell of the receptacle and rigidly supports said pipe 30. The pipe 37 is connected with the nipple 37^a and inserted through the proper opening in the pad 18, the nipple being screwed home as shown 65 in Fig. 5, so as to rigidly support the

pipe. The pad 18 is then secured to the enlargement 17 in suitable manner for instance, by means of the bolts 17^a. It will be noted that the receptacle and its elements may be assembled as a single unit separate 70 and independent of the shaft 13. By means of this arrangement the various elements carried by the receptacle may be removed and replaced without disturbing the shaft or its packing, and repairs may be made 75 without necessitating the cutting away of the wall of the receptacle to reach defective parts, as sometimes must be done with apparatus now in general use.

It will also be observed that the valves 80 41 and 42 are of standard construction, i. e., the valve bodies are attached to straight stems which loosely engage the guide portions of the valve casing, whereby said valves may be readily removed for regrinding and substitution of new ones, by first removing the screw caps 44^a and removing the springs 43.

It is to be understood that although but one cam 38 is illustrated as coöperating 90 with but two valves 41 and 42, the invention is not limited in this particular because the cams and valves may be duplicated to any number desired.

From what has been said it will be readily 95 understood that by means of the invention, the water of condensation is trapped in a convenient and efficient manner, and that it is automatically disposed of when a predetermined quantity has been accumulated, 100 the operations occurring intermittently and being controlled by the weight of the accumulated water and its relation to the center of gravity of the receptacle.

Having thus explained the nature of the 105 invention and described an operative manner of constructing and using the same, although without attempting to set forth all of the forms in which it may be made, or all of the forms of its use, what is claimed 110 is:—

1. An automatic pump of the character described comprising a rock-shaft having independent passage ways, a receptacle removably secured to said rock-shaft, a water 115 inlet pipe projecting longitudinally into said receptacle, a steam pipe also projecting into said receptacle, said pipes being removably supported independent of the rock-shaft, and in communication with the respective passageways in the latter, steam introducing means and vent means in communication with the passageway leading to the steam pipe, and means actuated by the rocking of said shaft for controlling 125 said steam introducing means and said vent means.

2. An automatic pump of the character described comprising a rock-shaft having independent passageways, a receptacle ex- 130

tending transversely across said rock-shaft and removably secured thereto, a water inlet pipe projecting longitudinally into said receptacle, a steam pipe projecting into said 5 receptacle, said pipes being removably supported independently of the rock-shaft and in communication with the respective passageways in the latter, steam-introducing means and vent means in communication 10 with the passageway leading to the steam pipe, and means actuated by the rocking of said shaft for controlling said steam-introducing means and said vent means.

3. An automatic pump of the character 15 described comprising a rock-shaft provided with an enlargement having independent chambers therein and passageways communicating with the respective chambers, a receptacle removably secured to the en- 20 larged portion of said rock-shaft, a water inlet pipe projecting longitudinally into the receptacle, a steam pipe projecting into said receptacle, said pipes being removably supported independent of the rock-shaft 25 and in communication with the respective chambers in the enlargement thereof, steam-introducing means and vent means in communication with the passageway leading to the steam pipe, and means actuated by the 30 rocking of said rock-shaft for controlling said steam introducing means and said vent means.

4. An automatic pump of the character 35 described comprising a rock-shaft having independent passageways, a receptacle removably secured to said rock-shaft, a water inlet pipe projecting longitudinally into said receptacle and in communication with one of said passageways, a nipple remov- 40 ably securing the water inlet pipe to the receptacle independently of the rock-shaft, a steam pipe also projecting into said receptacle, said steam pipe being removably supported independently of the rock-shaft 45 and in communication with the other pas- sageway, steam-introducing means and vent means in communication with the passageway leading to the steam pipe, and means actuated by the rocking of said shaft for 50 controlling said steam-introducing means and said vent means.

5. An automatic pump of the character 55 described comprising a rock-shaft having independent passageways, a receptacle re- movably secured to the rock shaft, a water inlet pipe projecting into said receptacle and supported independently of the rock- 60 shaft, a steam pipe projecting into the receptacle, a threaded nipple removably securing 65 said steam pipe to said receptacle inde- pendently of the rock-shaft, said steam pipe being in communication with the other passageway in the rock-shaft, steam-introducing means and vent means in communica- 70 tion with the passageway leading to the

steam pipe, and means actuated by the rock- 75 ing of said shaft for controlling said steam- introducing means and said vent means.

6. An automatic pump of the character 80 described comprising a rock-shaft having independent passageways, a receptacle removably secured to said rock-shaft, a water inlet pipe projecting into said receptacle, a steam inlet pipe also projecting into said 85 receptacle, threaded nipples supporting said pipes and removably engaging said receptacle, said pipes being in communication with the respective passageways in the rock- shaft, steam introducing-means and vent means in communication with the passage- 90 way leading to the steam pipe, and means actuated by the rocking of said shaft for controlling said steam-introducing means and said vent means.

7. An automatic pump of the character 95 described comprising a rock-shaft having an enlargement provided with independent chambers and passageways leading to the respective chambers, a receptacle having a pad removably secured to said enlargement, 100 a water inlet pipe removably secured to said pad and projecting into said receptacle, a steam pipe removably secured to said pad and also projecting into the said receptacle, said pipes being in communication with the 105 respective chambers in said enlargement, steam-introducing means and vent means in communication with the passageway leading to the steam pipe, and means actuated by the rocking of said shaft for controlling 110 said steam-introducing means and said vent means.

8. An automatic pump of the character 115 described comprising a rock-shaft having independent passageways, a receptacle ex- tending transversely across the shaft, means removably securing the receptacle to the shaft, a water inlet pipe and a steam pipe projecting into said receptacle, said pipes being supported independently of the rock- 120 shaft and in communication with the re- spective passageways in the latter, a valve chamber communicating with the passage leading to the steam pipe, said valve chamber having a steam inlet branch and a vent branch, standard valves controlling said branches, means removably retaining said valves in place, and means actuated by the rock-shaft for alternately unseating said 125 valves.

9. An automatic pump of the character 130 described comprising a rock-shaft having independent passageways, a receptacle mounted on said rock-shaft and movable therewith, a water inlet pipe projecting into said receptacle, a steam pipe also project- 135 ing into said receptacle, said pipes being in communication with the respective passageways in the rock-shaft, a valve casing hav- ing a chamber communicating with the pas-

sageway leading to the steam pipe and provided with a steam inlet branch and a vent branch, each branch having a valve seat, valves removably mounted in said branches 5 and coöperating with said seats, each valve having a depending stem, guide means engaging the respective valve stems, springs acting to normally seat the valves, and means operated by the rock-shaft for alternately unseating said valves.

10. An automatic pump of the character described comprising a rock-shaft having independent passageways, a receptacle secured to and movable with said rock-shaft, 15 a water inlet pipe projecting into said receptacle and in communication with one of said passageways, a steam pipe also projecting into said receptacle and in communica-

cation with the other passageways, a casing communicating with the passageway leading to the steam pipe and provided with a steam inlet branch and a vent branch, removable valves controlling the respective branches, each valve having a depending stem, guide means engaging the respective 25 valve stems, removable caps engaging the respective branches, springs interposed between the caps and the tops of the respective valves, whereby the valves are normally seated, and means operated by the rock-shaft for alternately unseating said valves.
